SHAKE SPLITTING MACHINE

James C. Butler, Vancouver, British Columbia,
Canada

Application November 6, 1934, Serial No. 751,766

8 Claims. (Cl. 144—162)

This invention relates to a power-driven shake splitting machine for the manufacture of shakes from blocks of wood previously sawn to the desired lengths of the shakes it is wished to manufacture.

My invention differs from all known machines for this purpose in that the shakes are split from the bottom face of the block and also from both ends of the block without the necessity of having to turn the block from end to end as is usual when making shakes by hand splitting them by the usual frow method to give to the shakes a tapering thickness from butt to tip as more specifically set out in United States Patent No. 1,663,905.

It is one of the objects of my invention to manufacture shakes more economically than other known methods, such as hand splitting or resawing of previously hand split shakes, or manufacturing imitation split shakes from thick shingles by surfacing one face to give the appearance of a split shake.

Another object of my invention is to provide a machine for splitting shakes from previously sawn blocks of wood that will operate more quickly and turn out a larger quantity in a given time than other known methods and machines.

Another particular object of my invention is to provide a machine of this character that will operate in both directions, that is, it will split off a shake both on the forward and backward stroke of the machine.

Another object of my invention is to provide a machine that will manufacture tapering split shakes from either end of the block without the necessity of having to reverse the block from end to end to provide the taper.

With these and other objects in view I have invented the machine which is the subject matter of this application and which is further described in the following specification and illustrated in the accompanying drawings forming part of this application and in which:

Figure 1 is a side elevation of the machine showing the power driven crank shaft connected by the connecting rod to the slidable cross head.

Figure 2 is a plan view of the machine showing the slide bed, stationary knife, carriage and tilting tables.

Figure 3 is a detail end view of one of the tilting tables.

Figure 4 is a detail view of one side of the slide mechanism for tilting the table. This view shows the contact arm at the end of the slide bar in contact with the slidable cross head.

Figure 5 is a view of the mechanism shown in

Figure 4 after it has been moved to the opposite end of the stroke to that shown in Figure 4. This view shows the contact finger secured at the centre of the slidable cross head in contact with the contact bar of the slide mechanism.

In these drawings like numerals indicate like parts, and the numeral 1 indicates a rectangular framework upon which is mounted a power driven sprocket shaft 2 which drives through the sprockets 3 and chain 4 the crank shaft 5 having a pair of crank arms 6 connected by the rods 7 to the slidable cross head 8.

The framework 1 has a pair of heavy longitudinal angle iron slides 9 fitted upon the inside top edge of the longitudinal stringers of the framework to comprise a slide bed, and the cross head 8 is slidable thereon.

Fitted between the longitudinal slides 9 is a pair of pivoted tables 10, and fitted intermediately of the latter is a stationary double edged knife 11 secured rigidly to the slides 9.

The knife 11 is secured to the underside of the angle iron slides 9 by bolts 12 having distance pieces 13 to provide a clearance between the knife 11 and slides 9.

The tables 10 are pivoted opposite each other upon pivot shafts 14 passing through the sides of the framework 1 and angle iron slides 9 and are provided with suitable pivot bearings 15.

On the underside of the inner and opposite ends of the tables 10 are secured roller shaft bearings 16 fitted with rollers 17 at the outer ends.

Positioned below the stationary knife 11 is a pair of slotted slide members 18 having a central cutaway portion 19 and slots 20.

These slide members 18 are positioned upon the inner sides of the framework 1 and below the angle iron slides 9, see Figures 4 and 5.

Fitted to the inner sides of the slide members 18 and spanning the central cutaway portion 19 is a slotted depth adjusting gauge 21 secured to the sides of the members 18 by cap screws 22.

The slide members 18 are slidable upon bolts 23 passing through the main longitudinal frame of the framework 1.

The slide members 18 comprise a bed for the rollers 17 fitted upon the inner ends of the pivoted tables 10 and by which the tables are caused to alternately tip in opposite directions when the machine is operating, and by means of the depth adjusting gauge 21 the tip or inclination of the tables 10 is controlled in relation with the cutting edge of the stationary knife 11 by which means the thickness of the shakes being manufactured is governed.

The slide members 18 are moved inwardly on the inward stroke of the machine through a pair of contact arms 24 secured upon the inner ends of the slide members 18 by the slideable cross head 8 and are moved in an opposite or outward direction by the contact finger 25 secured upon the side of the slideable cross head 8 and in the centre thereof striking the contact rod 26 secured rigidly between the slideable members 18, see Figures 4 and 5. The slide members 18 are moved in alternate directions by movement of the carriage at six inches from the end of the stroke of the carriage.

The slideable cross head 8 is secured to the slide bed 9 by guide pieces 27 secured upon distance pieces 28 on the underside to permit of the necessary clearance of the slides 9.

Bolted to the front side of the cross head 8 is a fabricated angle iron framework carriage 29 which is also slideable upon the slide bed 9 by being suitably secured thereon by guide and distance pieces after the manner of the cross head 8.

In operation a block of wood suitable for the making of shingles is positioned within the carriage frame 29 and upon one of the pivoted tables 10 and the machine started.

The longitudinal grain of the block of wood positioned within the carriage 29 coincides with the longitudinal stroke of the machine and the block is forced against the stationary knife 11 in a slightly inclined position coinciding with the tip or inclination of the table upon which the bottom face of the block was positioned and a natural split shingle is severed from the block of wood similar to those split from a block of wood by the use of a frow and manual means.

After completion of one stroke, say assuming the outward stroke, the block of wood still within the framework carriage 29 is tipped automatically on the opposite table 10 to that upon which it was originally positioned by being forced thereon by the outward stroke of the machine, and the block of wood is drawn against the stationary knife 11 by the carriage 29 tipped or inclined in a direction opposite to that in which it was forced against the knife on the outward stroke, and another shingle is severed off, and this process is continued until the block of wood is completely used.

One of the distinctive characteristics of this machine is the fact that all shingles split from the block of wood are from the bottom face of such blocks and also from both ends of the block without the necessity of turning the block endwise for this purpose.

Another important feature of the machine is the fact that there is no idle stroke to the machine when in operation, as a shingle is severed off the block of wood in the machine both on the inward and outward strokes.

Having now described my invention, what I claim and desire to be protected in by Letters Patent, is:—

1. A power driven shingle splitting machine comprising, a slide bed and a slideable reciprocating carriage frame and cross head mounted thereon, a pair of pivoted and tilting tables positioned intermediate of the sides of said slide bed, a stationary and double edged knife positioned intermediate of said tables and transversely of said slide bed, table tilting slides positioned below said slide bed, means engaging said slides and said reciprocating carriage whereby said slides are moved to cause said pivoted tables to alternately tilt as said carriage is reciprocated so that

a block of wood positioned within said carriage frame and upon one of said tilting tables is forced against said stationary knife tilted in one direction and drawn against said knife tilted in an opposite direction whereby shingles are caused to be split from the bottom face of said block of wood. 5

2. A power driven shingle splitting machine comprising a slide bed, a slideable reciprocating carriage frame and cross head mounted on said slide bed, a pair of pivoted and tilting tables positioned intermediate of the sides of said slide bed, a stationary double edged knife positioned intermediate the inner ends of said pivoted tables, table tilting slides positioned below said slide bed, a depth gauge mounted upon said tilting slides whereby the tilt of said pivoted tables may be adjusted, means in co-operative engagement with said tilting slides and said reciprocating carriage to predeterminedly move said slides and tilt said tables as said carriage is reciprocated so that shingles are alternately severed from the lower face of a block of wood placed upon one of the tilting tables when said machine is operated. 10 15 20 25

3. A power driven shingle splitting machine comprising, a slideable carriage member adapted to receive therein a block of wood, a pair of pivoted and tilting tables, a stationary double edged knife positioned intermediate of said tables, slide means engaging with said carriage to cause said pivoted tables to alternately tilt when said carriage is reciprocated so that when a block of wood is positioned within said carriage and the carriage is moved in one direction, the block 30 35 will be tilted by one table, and a shingle severed from the block and when the carriage is moved in the opposite direction the block will be oppositely tilted by the other table and a second shingle severed from the block. 40

4. A power driven shingle splitting machine comprising a slideable carriage member adapted to receive therein a block of wood, a pair of pivoted and tilting tables, a stationary double edged knife positioned intermediate of said tables, slide means engaging with said carriage to cause said pivoted tables to alternately tilt when said carriage is reciprocated so that when a block of wood is positioned within said carriage the alternate ends of said block of wood are forced 45 50 alternately against said stationary knife and shingles severed from the bottom face of said block of wood as said machine is operated.

5. A power driven shingle splitting machine comprising a slideable carriage member adapted to receive therein a block of wood, a pair of pivoted and tilting tables, means to cause said tables to alternately tilt as said carriage is reciprocated, a stationary double edged knife positioned intermediate of said tilting tables, means controlling 55 60 the tilt of said tables in relation with the edge of said stationary knife whereby the thickness of the shingles being manufactured is determined.

6. A power driven shingle splitting machine comprising, a rectangular framework, stationary slides mounted on each side of said framework, a crank shaft connected to a slideable cross head mounted upon said slides, a carriage frame connected to said cross head, said carriage frame adapted to receive therein a block of wood, a pair of pivoted tables positioned intermediate of said slides, a stationary double edged knife positioned intermediate of said tables and transversely of said framework, slide means engaging with said carriage to cause said pivoted tables to 70 75

- alternately tilt when said carriage is reciprocated whereby a block of wood positioned within said carriage and upon one of said pivoted tables is forced against said stationary knife tilted in one direction and drawn against said knife tilted in an opposite direction and shakes severed off the bottom face by cuts starting at the alternate ends of said block of wood when said machine is operated.
- 5 7. A power driven shake splitting machine, comprising a rectangular framework, a crank shaft mounted upon said framework, a pair of crank arms mounted upon said crank shaft, stationary slides mounted upon the top and each inner side of said framework, a slidable cross head mounted upon said slides, a pair of connecting rods mounted upon said cross head and crank arms whereby said cross head may be reciprocated, a rectangular carriage frame connected to said cross head slidable upon said slides, a pair of tilting tables positioned intermediately of said slides, a stationary double edged knife secured transversely of said framework to said slides, and intermediately of said tilting tables,
- 10 slides positioned upon the inner sides of said framework and below said tilting tables, means engageable with said cross head and said slides adapted to move said slides in timed relation with the movement of said carriage whereby said tables are caused to tilt alternately with the movement of said carriage when said machine is operated in virtue of which tapered shakes are split off the bottom face of a block of wood positioned within said carriage frame through being forced against said stationary knife and while said block of wood is in a tilted position, passed from one of said tilting tables to the other.
- 15 8. In a machine of the class described, a pair of spaced apart tiltable tables, a double edged knife located between the spaced apart tables, a carriage reciprocably mounted above said tables and knife, to move in a single plane, and to receive a block of wood to rest on said tables, means to reciprocate said carriage and means to tilt 20 said tables on horizontal axes at right angles to the direction of the movement of said carriage as said carriage is reciprocated.

JAMES C. BUTLER.
